UNITED STATES PATENT OFFICE.

JOSEPH F. GLIDDEN, OF DEKALB, ILLINOIS.

STOCK TROUGH OR TANK.

SPECIFICATION forming part of Letters Patent No. 678,104, dated July 9, 1901.

Application filed November 15, 1900. Serial No. 36,618. (No model.)

To all whom it may concern:

Be it known that I, JOSEPH F. GLIDDEN, of Dekalb, county of Dekalb, and State of Illinois, have invented certain new and useful 5 Improvements in Stock Troughs or Tanks, of which the following is a specification.

My invention relates to troughs or tanks for use in feeding or watering stock; and the object of my invention is to produce a strong, 10 durable, and inexpensive tank for general use on stock-farms, &c., requiring no supporting frame or structure, but adapted to rest on its own base and readily removable from place to place and at the same time possessing sufficient stability to satisfactorily 15 serve in its intended use.

What I regard as the principal novel features of my invention are the use of head-pieces of cement of considerable thickness 20 and the means for securing the latter in the body of the trough for the purposes and with the advantages hereinafter specified.

My invention is illustrated in the accompanying drawings, in which—

25 Figure 1 is a side elevation, partly in vertical section, of a trough built in accordance with my invention. Fig. 2 is a plan view of the same; and Fig. 3 is a vertical transverse section through one end or head of the trough, 30 showing the manner of securing the head-piece in place in the trough-body.

Referring to the drawings in detail, A represents the trough-body, which will preferably be of substantially semicylindrical shape 35 and may be rolled from any suitable sheet metal.

B designates the headpieces, which in accordance with my invention are made of cement in the form, as here shown, of substantially 40 semidisk-shaped blocks of considerable thickness and weight. The manner of securing these cement head-blocks in place is an important feature of my present invention and is performed as follows: Across and 45 between the opposite sides of the trough-body, near the ends thereof, are passed a series of wires C, the returning or meeting ends of which are preferably united by being simply twisted and tied together in the manner 50 plainly shown in Fig. 3. Directly above these wires and also further uniting the opposite sides of the trough-body are tie-bolts D, the latter also passing through the opposite sides of a rectangular wooden frame E, which

forms a binding for the upper edge of the 55 trough. The parts enumerated having been thus secured together, a body of plastic cement is molded in place in each end of the trough-body, entirely surrounding that part of said wires and tie-bolts which is within the 60 trough-body and shaped up into the form of head-blocks of uniform and considerable thickness and then allowed to harden in place, thus securely embedding therein the wires C and the end tie-bolts D. The binding-frame E and the tie-bolts D, of which there may be one or more intermediate the 65 head-blocks, according to the length of the trough, serve to secure the parts rigidly together laterally. The head-blocks B, made 70 of cement and secured in place in the manner and by the means specified, form an exceedingly strong and durable construction capable of withstanding great endwise strain, such as might be produced by the freezing of 75 water in the trough, and in addition thereto by reason of their weight they add to the general stability of the trough, rendering it less easy to be displaced or overturned.

I do not limit myself to the substantially 80 semicircular contour of the body of the trough herein shown, but prefer the same on account of its superior ease and cheapness of construction.

I claim as my invention—

1. The combination with the trough-body and the cement head-blocks, of wires connecting opposite sides of the trough-body and embedded in said cement head-blocks.

2. The combination with the trough-body 90 and the cement head-blocks, of wires connecting opposite sides of the trough-body and embedded in said cement head-blocks and tie-bolts extending transversely of the trough.

3. The combination with the trough-body 95 and the cement head-blocks, of wires connecting opposite sides of the trough-body and embedded in said cement head-blocks, a rectangular binding-frame around the upper edge of the trough-body, and a series of tie-bolts extending transversely through the trough-body and binding-frame, the end tie-bolts being embedded in said cement head-blocks.

JOSEPH F. GLIDDEN.
